UNITED STATES PATENT OFFICE.

JESSE LLRENO FUSNER, OF WELLSBURG, WEST VIRGINIA, ASSIGNOR TO JOHNSON MANUFACTURING COMPANY, OF URBANA, OHIO, A CORPORATION OF OHIO.

OILER.

1,304,301.

Specification of Letters Patent. Patented May 20, 1919.

Application filed February 23, 1918. Serial No. 218,838.

To all whom it may concern:

Be it known that I, JESSE L. FUSNER, a citizen of the United States, residing at Wellsburg, in the county of Brooke and

5 State of West Virginia, have invented certain new and useful Improvements in Oilers, of which the following is a specification.

The present invention relates to oilers, and particularly hand oilers of the type in 10 which the discharge of lubricant can be controlled.

One of the primary objects is to provide a practical structure of this character, which is at the same time simple in its make-up, 15 is not liable to derangement, but is so constructed that the parts are accessible for repair and renewal.

A further and important object is to provide valve mechanism that will properly 20 shut off the flow of the lubricant when closed, the valve having a rectilinear movement toward and from its seat, and being allowed sufficient play to effect a proper seating action.

25 In the embodiment illustrated in the accompanying drawings:—

Figure 1 is a longitudinal sectional view through a hand oiler equipped with the novel valve mechanism.

30 Fig. 2 is a sectional view on the line 2—2 of Fig. 1.

Fig. 3 is a detail sectional view through the reservoir body at right angles to Fig. 1.

35 Fig. 4 is a detail view on an enlarged scale of the valve and valve seat.

Fig. 5 is a detail sectional view of the valve.

Fig. 6 is a detail sectional view on an enlarged scale through the coupling between 40 the spout and can or reservoir body.

Fig. 7 is a detail sectional view on the line 7—7 of Fig. 1, and

Fig. 8 is a detail view of the operating handle.

45 Similar reference numerals designate corresponding parts in all the figures of the drawings.

In the embodiment disclosed, the can or reservoir body 9 may be of any desired 50 structure, and is provided with an upstanding threaded nipple 10 terminating in an inset wall 11 spaced from the threaded portion. A tapered spout 12 is employed having its larger end crimped or otherwise 55 formed, to produce parallel opposite sides,

as indicated at 13. On this portion 13 is fixed, as by brazing, welding, soldering or the like, a reinforcing collar 14 having at its outer end an outstanding stop flange 15. The said larger end 13—14 fits snugly with- 60 in the inset wall 11 of the nipple, as clearly shown in Fig. 6, and interposed between the upper end of said nipple and the flange 15, is a packing gasket 16. A threaded cap 17 screwed upon the nipple 10 has an inset 65 flange 18 that overlies the stop flange 15, and is preferably corrugated, as shown at 19 to stiffen the same.

In the outer portion of the spout 12 is a valve seat member, preferably constructed 70 of sheet metal, and comprising a transverse partition 20 having an outwardly tapered discharge opening forming the seat, this partition also having an inwardly extending annular flange 21. The flange fits snugly 75 against the walls of the spout 12 and the seat member thus produced is suitably fixed within said spout, as for example by having the walls of the spout indented, as shown at 23 on opposite sides of the member. A 80 valve stem 24 is slidably mounted in the stem and extends into the can body 9, the outer end of this stem having a head 25 on which is mounted a valve in the form of a hollow body 26 that surrounds the head 25, 85 and has a slight amount of play thereon. The stem furthermore has secured to it a guide spider 27 adjacent to the head, and serving to maintain the stem in centered relation, this spider sliding within the spout 90 12, as will be readily understood.

The can body or reservoir is provided with a transverse supporting bar 28 fixed at its ends to the walls thereof, and carrying an offset keeper 29 constituting a guide in 95 which the inner end of the stem is slidably engaged, the rear wall 30 of said guide being rounded, as clearly shown in Fig. 3 so as to reduce the bearing surface for the stem.

Journaled in one wall of the body 9 is a 100 rock shaft 31, the inner end of which is rotatably mounted in the supporting bar 28. The journal bearing for the outer end of the shaft is in the form of a packing gland comprising a casing 32 through which the shaft extends, a plug 33 being threaded into the outer end of the casing and the packing 34 being located in the latter behind the plug. The outer end of this shaft 105 is provided with a suitable operating handle 110

35, and its inner end has fixed thereto a gear segment 36 that extends into the guideway formed between the keeper 29 and supporting bar 28. The lower end 37 of the 5 valve stem 24 is smooth, and just above said smooth portion, said stem is provided with rack teeth 38 arranged to mesh with the teeth of the gear segment 36 when the rock shaft is rotated. In normal condition, however, as shown in Fig. 3, the teeth are out 10 of mesh so that the valve stem 24 can be withdrawn from the guideway and the reservoir body 9. To maintain the parts in the position shown in Fig. 3, a coiled spring 39 15 surrounds the shaft 31, and has one end connected as shown at 40 to a rearwardly extending finger 41 on the gear segment, the other end of the shaft being engaged, as illustrated at 42, with the supporting bar 28.

20 Briefly described, the operation of the device is as follows: With the parts as shown in Figs. 1, 3 and 4, the valve is closed, the lowermost teeth 38 bearing upon the teeth of the gear segment 36, so that the valve is held closed and cannot be accidentally 25 opened except against the action of the spring. If, however, the handle 35 is pressed downwardly, the gear segment will be turned, causing the teeth to intermesh and 30 moving the valve stem 24 inwardly. This causes the valve to be unseated to permit the outflow of lubricant. Upon releasing the handle 35, the spring 39 will react to close the valve.

35 With this construction, it will be evident that the valve and valve stem have a strictly rectilinear movement, the valve stem and valve, even when the latter is opened, is maintained centrally within the spout, so that it 40 will not materially interfere with the flow of the oil, and in addition it prevents binding at the inner end of the stem. The valve will always seat itself properly, and any slight inaccuracy in the valve seat will be accommodated by the play of the valve 26 upon 45 the head 25. When the spout is removed, the valve and stem can also be readily detached inasmuch as the teeth 38 and gear segment 36 will be out of mesh. Furthermore 50 the structure insures proper coöperation of the valve and valve seat even if there is a variation in the position of the valve, for when the spout is screwed down the valve will seat itself and any excess length 55 of the stem will cause the teeth to intermesh and turn the gear segment slightly to accommodate the same. The parts obviously are simple in form and can be easily and cheaply manufactured and assembled, their proper functioning after assembly being 60 assured because of the relation as above set forth.

From the foregoing, it is thought that the 65 construction, operation and many advantages of the herein described invention will

be apparent to those skilled in the art, without further description, and it will be understood that various changes in the size, shape, proportion and minor details of construction may be resorted to without departing 70 from the spirit or sacrificing any of the advantages of the invention.

What I claim, is:—

1. In an oiler, the combination with a reservoir body having a delivery spout, of a 75 valve seat member within the spout comprising a sheet metal partition having a valve seat and an annular flange extending alongside the walls of the spout, said walls being indented to hold the seat in place, and a 80 valve movable into and out of coaction with the seat.

2. In an oiler, the combination with a reservoir body having a nipple provided with an inset wall, of a tapered spout having its 85 larger end provided with substantially parallel cylindrical sides, a collar fixed on said larger end and having an outstanding stop flange at its upper end that abuts against the nipple, said collar fitting within the inset 90 wall, and a cap detachably engaged with the nipple and extending over the stop flange.

3. In an oiler, the combination with a reservoir body having a delivery spout, of a valve seat, a valve movable into and out of 95 coaction with the seat and having a stem, an operating device in the body, and a gear connection between the operating device and stem to effect a longitudinal rectilinear movement of the stem to carry the valve into and 100 out of coaction with the seat, said gear connection being detachable and permitting the separation of the stem and operating device when the spout is removed, said spout when in place maintaining the gear connection in 105 operative condition.

4. In an oiler, the combination with a reservoir body having a detachable delivery spout, of a valve seat, a removable valve 110 movable into and out of coaction with the seat and having a stem, a rack on the stem, and an operating shaft journaled on the body and having a gear in detachable mesh with the rack to permit the removal of the stem when the spout is removed, said spout 115 when in place maintaining the rack and gear in coöperative relation.

5. In an oiler, the combination with a reservoir body having a delivery spout, of a 120 valve seat, a valve movable into and out of coaction with the seat and having a stem, a rack on the stem, an operating shaft journaled on the body and having a gear detachably in mesh with the rack, and a spring operating on the shaft for returning the valve 125 to closed position when opened by the operating shaft.

6. In an oiler, the combination with a reservoir body having a delivery spout, of a 130 valve seat, a valve movable into and out of

coaction with the seat and having a stem, a rack on the stem, a guide member for the stem located in the body, an operating shaft journaled in the body and guide member 5 and having a gear in mesh with the rack, and a spring surrounding the shaft and connected to the gear and guide member.

7. In an oiler, the combination with a reservoir body, of a spout carried thereby, a 10 valve seat in the spout, a valve coöperating with the seat and including a stem extending into the reservoir body, a supporting bar extending across the body and having a guide for the inner end of the valve stem, a rock 15 shaft journaled in the reservoir body and the supporting bar, a rack on the portion of the valve stem operating in the guide, a gear segment fixed to the rock shaft and operating in the guide, said gear meshing with the 20 rack upon the operation of the rock shaft but being free therefrom, to permit the removal of the stem when in its normal posi-

tion, and a spring for holding the shaft and gear segment in such normal position.

8. In an oiler, the combination with a 25 reservoir body, of a spout detachably mounted thereon and having a valve seat therein, a valve in the spout movable into and out of coaction with the seat and having a stem projecting into the reservoir body, 30 an operating device mounted in the reservoir body, detachable connections between the operating device and valve stem to effect the operation of the valve and to permit the removal of the valve and stem from the body 35 and the spout when the latter two are separated, and yielding means engaged with the actuating device to return the valve to closed position, and to accommodate for any inaccuracies in the relations of the different 40 parts when the same are assembled.

In testimony whereof I affix my signature.

JESSE LLRENO FUSNER.
